DESIGN FOR A SLIP

Harry Cohen, New York, N. Y.

Application April 20, 1937, Serial No. 68,885

Term of patent 3½ years

To all whom it may concern:

Be it known that I, Harry Cohen, a citizen of the United States of America, residing in city of New York, county of New York and State of New York, have invented a new, original, and ornamental Design for a Slip, of which the following is a specification, reference being had to the accompanying drawing, forming part thereof.

Fig. 1 is a front view of a slip showing my new design.

Fig. 2 is a rear view thereof.

I claim:

The ornamental design for a slip substantially as shown.

HARRY COHEN.
